FLEXIBLE ELECTRODE SUPPORT FOR
ELECTRON DISCHARGE DEVICES

Ross Wood, Waltham, Mass., assignor to Raytheon Manufacturing Company, Newton, Mass., a corporation of Delaware

Application March 8, 1946, Serial No. 652,927

8 Claims. (Cl. 250—27.5)

1

This invention relates to electron-discharge devices, and more particularly to the means by which filamentary cathodes are held in tension within the device.

A large number of devices for supporting filaments in tension within an electron-discharge device have been conceived but their use has been confined to electron-discharge devices of the well known conventional size. With the advent of sub-miniature electron-discharge devices such as are used in hearing-aid apparatus, pocket-size radio receivers and other electronically-operated devices where extreme compactness is a first requisite of construction, the importance of properly spacing and positioning the minute elements within these sub-miniature electron-discharge devices poses a very difficult structural problem, namely, means for properly maintaining a directly heated filament in proper space relation to the control grid within the confines of an extremely small envelope having an internal diameter of the order of 0.2 of an inch. Cantilever spring suspensions as ordinarily used in some miniature tubes, particularly those of a size somewhat larger than the present device, present many difficulties when an attempt is made to use them in the sub-miniature type tubes. Such a cantilever structure when scaled down to meet the needs encompassed in a tube having a diameter as just described would, by reason of its diminishing size, lose its elastic characteristic which is so essential to maintaining and supporting a filament in tension.

It is therefore an object of the present device to provide a filamentary support which will have a cantilever spring action in the longitudinal plane of an electron-discharge device in contradistinction to a cantilever structure in the transverse plane as commonly used.

It is a further object to provide a support for a filament which is a unitary structure capable of being deformed without acquiring a set in the deformed position.

These and other objects will present themselves as the specification progresses and as evidenced by the attached drawing in which:

Fig. 1 is a cross-sectional view of one embodiment of the invention; and

Fig. 2 is a second embodiment, in cross section, of the present invention.

Referring now more particularly to Fig. 1, the drawing illustrates an evacuated envelope 10 containing therein electrode spacers 11 and 12, composed of mica for example, which serve to position the anode electrode 15 within the envelope 10.

2

The spacers 11 and 12 are provided with apertures 17, 23, 24 and 25 through which are threaded the filamentary cathode 14 and the filament support 13. For the sake of clarity the usual control grid has been omitted. However, the device can be used in combination with any number of electrodes.

The metallic support 13, which may be composed of tungsten for example, is rigidly affixed, as by welding, to a metal tab 16 and extends on through the aperture 17, said tab being in turn fastened to the edge of insulating spacer 12 by crimping thereto, or by any other suitable means. The free end of support 13 extends through aperture 23 in spacer 11 and terminates in a short arm 13A. The filament 14 has tabs 20 and 21 affixed to each end thereof as by welding or other suitable means. The tab 20 is welded to the end of the short arm 13A of the support and the tab 21 welded to the cross bar 18 which in turn is fastened, preferably by welding, to the downwardly extending member 18A, said last-named member being riveted or otherwise firmly fastened to the spacer 12. The manner of assembling the support 13 and filamentary cathode 14 will be given in more detail hereinafter.

Electrically-conductive members 19 and 19A are firmly imbedded within the press 22, said press being an integral part of the envelope 10. The members 19 and 19A serve to support the electrode assembly within the envelope 10 and to conduct current to the respective electrodes. Lead 19 is welded to the cross member 18, said cross member acting as a support for one end of the filamentary cathode 14. Lead 19A is welded to the lower end of support 13 which projects through aperture 17. This assembly provides a path for the conduction of current through the filamentary cathode 14 when a potential is applied between the leads 19 and 19A.

In the construction of the device, the length of the filament 14 is first determined. Tabs 20 and 21 are then welded to the respective ends of said filament. Tab 20 is then welded, or otherwise fastened to the spring arm 13A. Now tab 21 is dropped through the apertures 24, 25, spring arm 13A is depressed and tab 21 welded to the cross member 18. This arrangement causes the support 13 to bow out or distort and so provide the necessary tension in filament 14. Thus we have provided a unitary supporting structure, simple in its configuration, small in that portion which must lie in the transverse position within the device, yet providing a tension arrangement

which is so resilient that it will not take a set in the deformed position.

Fig. 2 illustrates a second embodiment of the present device in which the support is a flexible metal member 26, preferably composed of tungsten. This structure permits even greater latitude in reducing the size of the envelope 10. Its advantages will be taken up as this specification progresses. In this particular embodiment, the tab 21 is fastened, by welding or otherwise, directly to the member 18A.

In Fig. 2, the short arm 13A is dispensed with to enable the construction of devices of the type described having still smaller internal diameters. Here the construction of the support 26 is in the nature of a half-portion of a string and bow arrangement, the tab 16 being the point of fulcrum. In this particular embodiment the construction is simplified further by threading the filament 14 through the apertures 24 and 25 and fastening the tab 21 directly to the member 18A, thus obviating the extended member 18. As can be readily observed the tension in the filament is similar to the tension in the string of a bow which has been pulled taut.

Although several embodiments of this invention have been described and illustrated, it is of course understood that many modifications and alterations may be made wherein the relation of the electrodes may be altered to achieve the primary conception of this invention; for example, a plurality of filament supports may be placed diametrically opposite each other for the purpose of constructing a dual diode or triode having separate filaments within the small space as hereinbefore described, or such supports may be readily used in tubes of larger diameter with equal effectiveness.

What is claimed is:

1. An electrode support comprising a flexible member of unitary construction, a major portion of the length of said member being substantially parallel with an electrode attached thereto, means for rigidly supporting one end of said member, means for fastening said electrode to the unsupported end of said flexible member, and means for rigidly supporting the opposite end of said electrode to cause said flexible member to distort under tension.

2. An electrode support comprising a flexible L-shaped member, means for rigidly fastening one end of an electrode to one arm of said member, means for rigidly supporting the other arm of said member, and means for rigidly fastening the opposite end of said electrode to cause said member to distort under tension.

3. An electrode support comprising a flexible L-shaped member having arms of substantially differing lengths, means for rigidly fastening one end of an electrode to the shorter arm of said member, means for rigidly supporting the end of the longer arm of said member, and means for rigidly fastening the opposite end of said electrode to cause said member to distort under tension.

4. An electrode support comprising a flexible unitary L-shaped member having arms of substantially differing lengths, the longer arm of said member being substantially parallel with an electrode attached to the end of the shorter arm

thereof, means for rigidly fastening one end of said electrode to the end of the shorter arm of said member, means for rigidly supporting the end of the longer arm of said member, and means for rigidly fastening the opposite end of said electrode to cause said member to form a bow under the tension.

5. In an electron discharge device, the combination of an envelope containing an electrode assembly, insulating spacers having apertures therein for the passage therethrough of said electrodes, at least one of said spacers having a metal tab attached to the edge thereof, a second metal tab attached to said first-named spacer, said second-named tab being disposed between said first-named tab and an aperture in the center of said spacer, an electrode support comprising a flexible metal member, a major portion of the length of said member being substantially parallel with an electrode attached to one end thereof, the opposite end of said member being rigidly affixed to said first-named tab, and the other end of said electrode being attached to said second-named tab to cause said support to distort under tension.

6. In an electron discharge device, the combination of an envelope containing electrode spacing means, at least one of said spacing means having means for rigidly attaching thereto at least one electrode, said spacing means having apertures therein for the passage therethrough of said electrode, an electrode support comprising a flexible unitary member, a major portion of the length of said support being substantially parallel with an electrode attached thereto, said support being rigidly attached to a first of said spacing means, the free end of said support extending through an aperture in a second of said spacing means, and means for attaching said electrode to the free end of said support, the opposite end of said electrode being firmly affixed to said first-named spacing means to cause said support to distort under tension.

7. An electrode support comprising a unitary member having arms of substantially differing lengths, the shorter of said arms being relatively rigid with respect to the longer of said arms, means for attaching one end of an electrode to the shorter arm of said member, and means for attaching the opposite end of said electrode to cause said longer arm to distort under the tension.

8. An electrode support comprising an L-shaped member of unitary construction having arms of substantially differing lengths, the shorter of said arms being relatively rigid with respect to the longer of said arms, means for attaching one end of an electrode to the shorter arm of said member, and means for attaching the opposite end of said electrode to cause said longer arm to distort under the tension.
